Primary Examiner — Paula Allen Greene(74) *Attorney, Agent, or Firm* — Stanek Lemon Crouse & Meeks PA(57) **CLAIM**

The ornamental design for headphones with conical earpieces, as shown and described.

DESCRIPTION

FIG. 1 is a front perspective view of the headphones with conical earpieces showing the design;

FIG. 2 is a front view thereof;

FIG. 3 is a rear view thereof;

FIG. 4 is a side view thereof;

FIG. 5 is a side view opposite that shown in FIG. 4;

FIG. 6 is a top view thereof;

FIG. 7 is a bottom view thereof; and,

FIG. 8 is a cross-section taken from the view of FIG. 2. The broken lines shown in the drawing views are included for the purpose of illustrating portions of the headphones with conical earpieces that form no part of the claimed design.

1 Claim, 6 Drawing Sheets(56)
